HAND BANDAGING UNIT

Filed April 1, 1949

UNITED STATES PATENT OFFICE

2,561,863

HAND BANDAGING UNIT

Faith Holm, North Chatham, Mass.

Application April 1, 1949, Serial No. 84,840

2 Claims. (Cl. 128—157)

1

The present invention relates to hand bandaging means, and more particularly to a unitary mitten-like structure serving as a bandage for the hand.

One of the difficulties encountered in applying surgical bandages to the hand is that the bandage must be wrapped in a manner whereby the person is practically completely disabled from using the fingers of the hand, even in cases where the injury to the hand otherwise would not prevent full or partial usefulness of the fingers. This is particularly annoying because the injured person thus is less useful and requires greater attention, assistance, and care from others. As a result, the injured person may be required to remain absent from his place of employment and may lose compensation for the failure to perform his services.

Accordingly, an object of the present invention is to provide an improved hand bandaging unit which overcomes the foregoing difficulties and disadvantages.

Another object is to provide a hand bandaging unit which does not prevent usefulness of the fingers.

Another object is to provide a hand bandaging unit of the foregoing character which is simple in construction and is economical to manufacture.

Another object is to provide a hand bandaging unit of the foregoing character which is easily applied with a minimum of skill, thus minimizing the amount of professional attention heretofore required for rebandaging the injury during the healing thereof.

A further object is to provide a hand bandaging unit which is adapted to be washed and sterilized thereby enabling it to be reused several times.

Other and further objects will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawing, forming a part of the specification, wherein:

Figure 1 is a developed plan view of a blank from which the hand bandaging unit in accordance with the invention is constructed.

Figure 2 is a plan view on a reduced scale of the completed hand bandaging unit.

2

Figure 3 is a perspective view illustrating the bandaging unit partially applied to the hand.

Figure 4 is a perspective view of the back of the hand with the bandaging unit applied.

Figure 5 is a perspective view of the palm of the hand with the bandaging unit applied.

Referring to the drawing in detail and more particularly to Figure 1 thereof, there is shown a substantially rectangular fabric blank 10 from which the hand bandaging unit is constructed. The blank has a V-shaped notch 11 at its upper end (which becomes the forward end of the unit with respect to the hand) substantially at the middle thereof defined by the broken line 12, and has an aperture 14 along the line 12 adjacent but spaced from the notch 11. Both of the upper or forward corners of the blank are formed with arcuate cutaway portions or recesses 15, whereby the lower portions (or palm and wrist portions for the hand) at the sides extend further outwardly to provide flaps 16 to which a strap 17 is secured. A pair of vertical slits 18 is formed in the body just below the aperture 14 and to one side thereof. The function of the elements will become apparent from the description about to follow.

In Figure 2 the blank is shown folded along the center line 12 and sewn at the upper or forward portion thereof by longitudinal parallel stitching 19, 20, and 21 to provide a plurality of individual finger openings. The aperture 14 provides an opening through which the thumb is adapted to extend; the fold at 12 and the stitching 19 cooperate to provide an opening for the index finger; the stitching 19 and 20 cooperate to provide an opening for the middle finger; the stitching 20 and 21 cooperate to provide an opening for the ring finger; and the stitching 21 spaces the ring finger and little finger whereby the latter is adapted to extend outwardly of the recesses 15. The slits 18 may be used selectively in conjunction with the straps 17, to enable the unit to accommodate hands of various sizes.

In Figures 3, 4, and 5, the bandaging unit is illustrated applied to the hand. In order to apply the unit the thumb, index finger, middle finger, and ring finger are inserted through their respective openings as shown. A compress or other dressing (not shown) is placed on the injured portion of the hand, and the flap 16, shown in broken lines (Figure 3), is folded about the back of the hand and tucked under the other flap thereby enabling the little finger to extend outwardly beyond the recesses 15 of the flaps. The strap 17 of the aforementioned flap extends about

the top of the wrist, within the unit, and is passed outwardly through one of the slits 18 positioned at the underside of the wrist. The other flap 16 is then folded inwardly under the palm of the hand (Figure 5), and the strap 17 and this flap is tied in a bow or is knotted to the other strap. In lieu of the straps 17, the wrist portions of the unit could be secured together about the wrist by adhesive tape.

As will be seen in Figures 4 and 5, the unit provides a mitten-like structure for the hand which enables the injured person to move the thumb and fingers and thereby retain at least partial usefulness of the hand.

From the foregoing description, it will be seen that the present invention provides a simple and practical hand bandaging unit which is economical to manufacture, and can be readily applied to the hand.

It will be understood that the unit may be formed of any suitable pliable fabric, for example surgical gauze, cotton or linen cloth, cloth or films of synthetic materials, or rubber, or any of the foregoing fabrics impregnated or otherwise treated to render them impervious. It will also be appreciated that the compress or dressing, if desired, may be embodied as a layer of the material from which the unit is constructed whereby the insertion of a compress is not required.

As various changes may be made in the form, construction and arrangement of the parts herein, without departing from the spirit and scope of the invention, as claimed, and without sacrificing any of its advantages, it is to be understood that all matters are to be interpreted

as illustrative and not in any limiting sense, except as limited by the claims.

I claim:

1. A hand bandaging unit comprising a fabric body in the form of a mitten having finger opening means divided to provide individual openings for the index, middle, and ring fingers, a thumb aperture at one side thereof, and an opening at the side opposite said thumb aperture extending from end to end of said last mentioned side, portions of said body adjacent a forward end of said last mentioned opening being recessed to enable the little finger to extend therethrough.

2. A hand bandaging unit comprising a fabric body in the form of a mitten having finger opening means at a forward end thereof, a thumb aperture at one side thereof, and an opening at the side opposite said thumb aperture extending from end to end of said last mentioned side to provide flaps adjacent said side opening adapted to be partially wrapped about the hand; and a strap secured to each flap for tying said body about the wrist.

FAITH HOLM.
